US0D1021910S

(12) **United States Design Patent** (10) **Patent No.:** **US D1,021,910 S**
(45) **Date of Patent:** **** Apr. 9, 2024**

(54) **HOLDER FOR ELECTRONIC DEVICES**

(71) Applicant: **Fidlock GmbH**, Hannover (DE)

(72) Inventor: **Björn Bleckat**, Hannover (DE)

(73) Assignee: **Fidlock GmbH**, Hannover (DE)

(**) Term: **15 Years**

(21) Appl. No.: **29/780,015**

(22) Filed: **Apr. 22, 2021**

(51) **LOC (14) Cl.** **14-03**

(52) **U.S. Cl.**

USPC **D14/253**

(57) **CLAIM**

The ornamental design for a holder for electronic devices, as shown and described.

DESCRIPTION

FIG. 1 is a front elevation view of a holder for electronic devices, showing my new design;

FIG. 2 is a right side elevation view thereof;

FIG. 3 is a bottom view thereof;

FIG. 4 is a top view thereof;

FIG. 5 is a rear elevation view thereof;

FIG. 6 is a left side elevation view thereof; and,

FIG. 7 is an upper perspective view thereof.

The dash-dash broken lines in the drawings are for the purpose of illustrating portions of the holder for electronic devices that form no part of the claimed design.

1 Claim, 7 Drawing Sheets
